Letters Patent No 2485. Dated Oct 2. 1866.

Design for a Book'store

The design is referred to in these Letters Patent and making a part of the same.

To all whom it may concern:

Be it known that I, Jacob Steffee of the City of Philadelphia in the State of Pennsylvania have originated and designed a new ornamental Pattern for the Plates of a Book'store, of which the following is a full, clear, and exact description, reference being had to the accompanying drawing, making part of this Specification.

The drawing represents a perspective view of the stove and the ornamental Design on the plates thereof.

The Design consists of the ornamental figures a, b, c, on the side plates; the ornamental figures d, e, f, f, on the front plates, and the ornamental figures g, g, on the legs, as shown.

What I claim as my invention and desire to secure by Letters Patent is
The ornamental Design for the plates of a Book'store as set forth and shown
Witnessed

By: Morrison.

Mr. G. Morrison.
